JUAN N. SILVA, OF WICKLIFFE, OHIO.

KILN ATTACHMENT.

Application filed April 9, 1924. Serial No. 705,325.

The present invention relates to certain new and useful improvements in kilns of that general type which are utilized for the burning of brick, pottery and other like products, and the object of the invention is to provide a battery of kilns having novel features of construction, whereby the heat from a kiln that is being fired is utilized for the preliminary heating of another kiln instead of being permitted to pass up the chimney and go to waste.

A further object of the invention is to provide a construction of this character which can be readily associated with any conventional form of kiln, either as an attachment or as a built-in part thereof, and which will result in a very considerable saving of fuel and reduce the cost of operating the kiln.

The invention also contemplates a device of this character which is comparatively simple and inexpensive in its construction, which can be readily applied to an old kiln or embodied in a new kiln, which will effect an economy in the amount of fuel required to fire the kiln, and which will tend to bring about an even burning of the contents of the kiln and reduce the quantity of seconds and defective products to a minimum.

With the foregoing and other objects in view the invention consists in certain combinations and arrangements of the parts as will more fully appear as the description proceeds; the novel features thereof being pointed out in the appended claims.

For a full understanding of the invention reference is to be had to the following description and accompanying drawings in which,

Figure 1 is a plan view of a battery of kilns which are constructed and equipped in accordance with the present invention, certain of the kilns being shown in section to illustrate more clearly the details of construction.

Figure 2 is a sectional view on the line 2—2 of Figure 1, with a part of one of the kilns shown in side elevation.

Figure 3 is a side elevation of a kiln in which the manifold is arranged under ground, part of the kiln being shown in elevation and part thereof being shown in section.

Figure 4 is a detail view of the portable fan.

Figure 5 is a detail view showing the means for suspending the portable form of the manifold on the kiln.

Figure 6 is a detail view showing one of the joints between the sections of the portable manifold.

Figure 7 is a detail view showing a possible modification in which the manifold branches extend downwardly to the lower furnace openings so that by reversing the fan the manifold can be used either to exhaust air from the manifold to draw the products of combustion from another kiln into the kiln and manifold, or to force air into the manifold to apply a forced draft to the furnaces when the kiln is being fired.

Corresponding and like parts are referred to in the following description and indicated on all of the views of the drawings by like reference characters.

The invention is adapted to be used in connection with a battery of kilns, and a possible grouping of six kilns is illustrated by Figure 1 of the drawings. For convenience in designating the various kilns the kilns have the reference letters A, B, C, D, E and F applied thereto. It will be understood that the exact arrangement or number of the kilns is immaterial to the invention, since the kilns may be arranged differently, and there may be either a greater or a smaller number of the kilns in the group or battery.

The kilns may be of any conventional construction, and each kiln is shown as comprising a circular wall 1 and a dome shaped top or crown 2, the circular wall being thickened at its lower portion where it is provided at suitable intervals with the furnaces 3. In the present instance each of the kilns is shown as provided with eight of these furnaces, and each furnace has its bag wall 4 which serves in the usual manner to carry the heat and products of combustion from the furnace to the top of the kiln. The furnaces 3 which are also shown are of the grateless type, the fuel being fed through the upper opening 3^a, while the ashes are removed through the lower opening 3^b. The usual annular band or bands 5 may extend around the upper portions of the circular kiln walls 1 for the purpose of preventing spreading of the walls.

Arranged under the floor of each of the kilns is a series of flues 6 which radiate from a central well 7. The floor flues 6

communicate with the openings 8 which extend through the floor of the kiln and the lower end of each of the wells 7 communicates with an underground tunnel or flue 9, which leads to the bottom of a stack 10. With the arrangements shown on Figure 1 of the drawings there are two stacks 10, and the kilns A and D have tunnels 9 communicating with one of the stacks, while the kilns B, C, E and F have tunnels 9 communicating with the other stack. Each of the stack tunnels or flues 9 is provided with a gate or valve 11, and each of the stacks 10 is also provided with a gate or damper 12. There are also underground tunnels or flues 13 connecting the kilns A and B, and the kilns D and E, each of these tunnels being provided with a gate or valve 14.

Ordinarily the various kilns are fired after they have been filled with the products to be burned and sealed. The products of combustion from the furnaces of the kiln that is fired are carried upwardly to the top of the kiln by the bag walls 4 and then circulate downwardly through the contents of the kiln, passing through the floor openings 8 into the floor flues 6, and thence through the well 7 and tunnel 9 to the stack 10. After a furnace has been fired the temperature of the interior thereof gradually increases until the proper temperature is reached, and the top of the kiln is the first to reach the proper temperature, the heat traveling downwardly through the great mass of the contents of the kiln at a rather slow rate. This requires considerable care and attention in the firing of a kiln to prevent over-burning at the top thereof.

According to the present invention the heat from a kiln that has been fired and which would ordinarily pass up the stack and be lost, is caused to circulate upwardly through another kiln so that the contents of this second kiln are given a preliminary heating before the second kiln is fired. Refer to Figures 1 and 2 of the drawings and let it be assumed that the kiln F is being fired and that the kiln B has been filled and is the next kiln to be fired. The gates 11 for the kilns E and C are closed, as is also the gate or damper 12 for the stack. The gate 14 of the tunnel 13 connecting the kilns A and B is also closed. The wells 7 of the kilns B and F are now in direct communication with each other, and the products of combustion from the kiln F will pass over to the bottom of the kiln B instead of going up the stack 10 and being wasted.

Surrounding the kiln B is a manifold 15, and this manifold is provided with a series of branch arms 16 which communicate with the furnaces 3. Suitable means such as the plates 17 can be provided for fitting over the furnace openings and the plates for the upper furnace openings may be suitably con-

structed to receive the branch arms 16 of the manifold. The lower furnace openings may be closed in any suitable manner as by means of plates or by banking with ashes or dirt. The manifold 16 is provided with an outlet 18 which is adapted to be connected by an elbow 19 to a fan 20. This fan may be preferably mounted so that it can be moved from place to place and is shown as mounted upon a truck 21. A suitable motor 22 is shown as provided for driving the fan, and the fan outlet is indicated at 23.

With the two kilns B and F connected up, as previously described, the kiln F being fired while the kiln B is ready for firing, the fan 20 is put in operation. This fan operates to produce a partial vacuum within the manifold 15 with the result that the products of combustion from the kiln F are forcibly drawn through the underground flues or tunnels 9 into the kiln B. The products of combustion circulate downwardly from the top of the kiln F to the bottom thereof and after passing through the underground flues circulate upwardly through the kiln B from the bottom to the top thereof, after which they pass down back of the bag walls 4 of the kiln B and are drawn into the manifold 15. The fan produces a positive draft for the kiln F and draws the products of combustion from the kiln F to the kiln B. These products of combustion pass through the kiln B in an upward instead of a downward direction, that is in a direction the reverse of that which is followed when the kiln itself is being fired. The heating of the contents in the kiln B is thus from the bottom to the top thereof, and the bottom of the kiln is thus well heated, so that when the kiln itself is eventually fired there is less resistance to the downward passage of the products of combustion from the furnaces of the kiln, and the kiln becomes heated more quickly and uniformly than would otherwise be the case. After the kiln B has been thoroughly heated by the products of combustion from the furnace F, the furnaces of the kiln B can be started to complete the firing of the kiln, and the products of combustion from the kiln B can be carried to one of the other kilns in the battery which is ready for firing. The preliminary heating of the kiln B by the products of combustion from one of the other kilns which would ordinarily go up the stack and be wasted results in the saving of a very considerable amount of coal in the firing of the kiln, and is conducive to much economy in the operation of the kiln. The pre-heating of the kiln also reduces or lowers the resistance which must ordinarily be overcome when firing a cold kiln to cause the products of combustion to pass freely through the contents of the kiln, and when the pre-heated kiln is eventually fired the contents thereof will heat much more quickly.

and uniformly than is ordinarily possible, with the result that there is less danger of over-burning and spoiling part of the contents.

5 The manifold 15 is of a type which can be applied as an attachment to kilns which have already been built, and to kilns which are arranged too close to each other or too close to the stack to permit of the installation of 10 an underground manifold. The manifold may be constructed of any suitable material such as sheet metal, and may be formed of a series of sections 15^a which are detachably connected to each other by any suitable form 15 of joint such as that indicated at 24 on Figure 6. The joint is formed by a band which encircles the abutting ends of the sections and may be drawn tightly together by a bolt or other fastening member. The manifold 20 may be mounted upon the kiln in any suitable manner, and, as indicated by Figures 2 and 5, the suspension cables or wires 25 may be used. These wires are looped to receive the manifold and the ends of the wires 25 detachably engage hook members 26 which are fitted upon one of the annular bands 5 of the kiln. The suspending wires can be readily disengaged from the hooks 26 and the manifold removed from the kiln. This 30 enables the manifold to be readily moved from one kiln to another kiln, and the fan 20 is also portably mounted upon the truck 21 so that it can be moved from place to place and used wherever it is desired to set 35 up the manifold.

The kiln D, as shown on Figure 1, has a manifold 27 which is located under ground, said manifold extending around the base of the kiln and being connected by the branches 40 28 to the furnaces thereof. The underground manifold 27 has a main branch 29 which extends upwardly to the surface of the ground and is adapted to be connected to the elbow 19 of the portable fan 20. This 45 elbow can be swung upwardly for connection with the raised manifold 15, or swung downwardly for connection with the underground manifold 27. The underground manifold operates in exactly the same manner as the over ground manifold. By reversing the fan or fan connection the underground manifold can also be used for supplying a forced draft to the furnaces of the kiln when the kiln is being fired.

55 A slight modification is shown by Figure 7, in which the branch arms 16^c of the manifold lead to the lower furnace openings 3^b instead of to the upper furnace openings. With this arrangement the manifold can be 60 used first for sucking or drawing the products of combustion from another kiln which is being fired upwardly through the kiln which is being preheated, and after the pre-heating has been completed and the kiln is

itself fired, the fan or fan connections can 65 be reversed so that the manifold arms will furnish a forced draft to the furnaces.

It will be obvious that by properly adjusting the gates and valves it may be possible to have two or more of the kilns in full 70 fire and to draw the products of combustion from these several kilns through one or more which are being preliminarily heated, or that it may be possible to distribute the products of combustion from a single kiln 75 which is being fired through two or more kilns which are being preliminarily heated, this being something which can be varied according to the judgment of the operator 80 in charge of the kilns.

Certain embodiments of the invention have been shown and described in detail for illustrative purposes, although it will be understood that many modifications and 85 changes can be made in the details of construction without departing from the spirit of the invention.

Having thus described my invention what I claim as new and desire to secure by Letters Patent is,

1. The combination with a group of kilns provided with the usual furnaces and floor flues, of a kiln connecting flue between the kilns, a manifold upon one of the kilns provided with branches leading to the furnaces thereof, and a fan connected to the manifold and adapted to be used either for pumping air into the manifold to apply a forced draft to the furnaces or for exhausting air 100 from the manifold to draw the products of combustion through the kiln connecting flue and into the kiln and manifold from another kiln which is fired and in the course of burning for drawing the products of combustion into the kiln and manifold from another kiln which is fired and in the course of burning.

2. The combination with a group of kilns provided with the usual furnaces, a stack, flues leading from the respective kilns to the stack, valves for the respective flues and stack whereby the kilns may either be connected to each other through the base of the stack or connected with the stack, and means for forcing the products of combustion through the flues from one kiln which is being fired to another kiln for the preliminary heating of the latter.

3. The combination with a group of kilns provided with the usual furnaces, a stack, flues connecting the respective kilns to the stack, valves for the flues and stack whereby any kiln can be placed in communication with the stack or with another kiln through the base of the stack, manifolds applied to certain of the kilns and provided with branches leading to the furnaces thereof, and means for forcibly exhausting air from the

manifolds to draw the products of combustion into the kiln and manifold from another kiln which is fired and in course of burning.

5. 4. The combination with a group of kilns provided with the usual furnaces and floor flues, kiln connecting flues extending between the floor flues of adjacent kilns, manifolds applied to certain of the kilns and 10 provided with branches leading to the furnaces thereof, and a portable exhaust fan adapted to be connected with the manifold of any selected kiln for drawing the products of combustion into the kiln and manifold from another kiln which is fired and in the course of burning.

5. The combination with a group of kilns provided with the usual furnaces and floor flues, kiln connecting flues, extending between the floor flues of adjacent kilns, manifolds for certain of the kilns, some of the manifolds being under ground and others being above ground, a portable fan, and an adjustable connecting member for connecting the same to any of the manifolds whether above or under ground, for drawing the products of combustion into the kiln and manifold from another kiln which is fired and in the course of burning.

39. 6. The combination with a group of kilns provided with the usual furnaces, kiln connecting flues, a portable manifold adapted to be applied to selected kilns and formed in sections, detachable joints, means for connecting the portable manifold to the kiln between the sections, and a fan for the manifold.

7. The combination with a pair of kilns having the usual furnaces in the side walls 40 thereof and provided with bottom flues, a kiln connecting flue extending between the bottom flues of the kilns, a portable manifold adapted to be selectively applied to either of the kilns and formed with branches 45 communicating directly with the furnaces of the kiln to which it is applied, and a suction fan connected to the manifold for forcibly drawing the products of combustion from the other kiln through the kiln connecting 50 flue into the kiln to which the manifold is applied, and thence into the manifold to preheat the contents of the second mentioned kiln, there being a down draft in the kiln that is burning and an up draft in the kiln 55 that is preheating.

8. The combination with a group of kilns having the usual furnaces, kiln connecting flues, a portable manifold adapted to be applied to a selected kiln, manifold suspending 60 means detachably engaging the kiln, means for connecting the manifold to the kiln, and a portable fan detachably connected to the manifold.

9. The combination with a group of kilns

provided with the usual furnaces, kiln connecting flues, hook members on the kilns, a manifold adapted to be applied to a selected kiln, manifold supporting elements detachably engaging the hook members, means for connecting the manifold to the kiln, and a 70 fan for the manifold.

10. The combination with a group of kilns provided with the usual furnaces and also provided with the usual kiln encircling bands, kiln connecting flues, hook members engaging the bands, a portable manifold adapted to be applied to a selected kiln, manifold supporting elements detachably engaging the said hook members, means for connecting the manifold to the kiln and 80 a fan for the manifold.

11. The combination with a group of kilns provided with the usual furnaces, of kiln connecting flues, a portable manifold adapted to be applied to a selected kiln and 85 formed with branches leading directly to the furnaces thereof, and a portable fan adapted to be detachably connected to the manifold.

12. The combination with a group of kilns 90 having the usual furnaces in the side walls thereof and provided with floor flues, a stack, flues extending between the floor flues of the respective kilns to the stack, valves for the flues and stack whereby any kiln can be 95 placed in communication with a base of the stack or with another kiln through the stack, manifolds applied to certain of the kilns and provided with branches leading to the furnaces thereof, and means for forcibly exhausting air from the manifolds to draw the products of combustion into the kiln and manifold from another kiln which is being burned, the products of combustion being 100 discharged from the manifold independently 105 of the stack, and there being a down draft in the kiln that is burning and an up draft in the other kiln.

13. The combination with a kiln formed 110 with a bottom flue and having the usual furnaces in the side walls thereof, of a manifold applied to the kiln and provided with branches leading to the furnaces thereof, and a fan associated with the manifold and adapted to be used either for pumping air 115 into the manifold to apply a forced draft to the furnaces or for exhausting air from the manifold to produce a reverse draft through the kiln.

14. The combination with a kiln having 120 the usual furnace openings in the side walls thereof, of a portable manifold extending around the kiln and formed in detachably connected sections, means for removably supporting the manifold upon the kiln above 125 the furnaces, branches leading from the manifold to the furnaces, and a portable fan detachably connected to the manifold.

15. The combination with a kiln provided with the usual furnaces and a floor flue, of a manifold extending around the kiln and provided with branches leading to the respective furnaces, of a fan connected with the manifold and adapted to be reversed so that it can be used either to exhaust air from the manifold or force air into the manifold.
16. The combination with a kiln provided with the usual furnaces and a floor flue, of a removable manifold provided with branches leading to the furnaces, means for

detachably mounting the manifold upon the kiln, and a portable fan for the manifold.

17. The combination with a kiln provided with the usual furnaces and a floor flue, of a manifold extending around the kiln and arranged above the furnaces, branches leading downwardly from the manifold to the furnaces, and a fan operatively connected to the manifold.

In testimony whereof, I affix my signature.
